UNITED STATES PATENT OFFICE.

HARRY B. RODGERS, OF CHAMBERSBURG, PENNSYLVANIA.

SANITARY SHAVING-BRUSH AND CONTAINER THEREFOR.

1,266,160.

Specification of Letters Patent.

Patented May 14, 1918.

Application filed June 15, 1915. Serial No. 34,274.

To all whom it may concern:

Be it known that I, HARRY B. RODGERS, a citizen of the United States, residing at Chambersburg, in the county of Franklin and State of Pennsylvania, have invented certain new and useful Improvements in Sanitary Shaving-Brushes and Containers Therefor, of which the following is a specification.

10 This invention relates to toilet articles and more particularly to a sanitary shaving mug and has as its object to provide an article of this class which may be discarded after having been once used and which may 15 be manufactured in large quantities at a low cost.

An aim of the invention is to provide an article of this class in which the body of the mug may be repeatedly used without, however, in any way rendering the article insanitary, the body itself being constructed of such material as to be capable of sterilization.

The invention aims further to so construct 25 the holder or body portion of the mug that, when the container portion is disposed within the holder or body portion, the said container portion will be caused to assume the shape of a cup in which the lather may be 30 produced.

In the accompanying drawings:

Figure 1 is a perspective view illustrating the article embodying the present invention in condition for use.

35 Fig 2 is a perspective view of one of the container portions of the mug separated from the other portions of its kind and in condition for insertion into the holder or body portion of the mug, the said figure illustrating also the said holder or body portion of the mug.

Fig. 3 is a vertical transverse sectional view through the mug in condition for use, on the line 3—3 of Fig. 4.

45 Fig. 4 is a perspective view of the completed mug.

Corresponding and like parts are referred to in the following description and indicated in all the views of the accompanying drawings by the same reference characters.

50 While the body portion or holder of the mug may assume various forms without departing from the spirit of the invention, the same preferably comprises a hollow cylindrical body 1 which may be of metal, glass, or any other material which may be readily

cleansed and sterilized, and this body is provided in its upper portion with a number of downwardly extending kerfs 2 which are substantially V-shaped, or, in other words, 60 restricted in width gradually in the direction of their lower ends. In the present instance, the body 1 is illustrated as formed with four such kerfs equidistantly spaced, although a greater or less number may be provided if found desirable. That portion of the wall of the body 1 between each two of the kerfs is turned outwardly to form an outwardly extending lip 3, the lip at the line of juncture of the said portion presenting 70 a rounded surface, indicated at 4, so as to permit of the more ready insertion, into the upper end of the support or body, of the container portion of the said mug. It is also preferable that the edges of the portions 75 which lie between the kerfs or, in other words, the walls of the kerfs be rounded or smooth for the same purpose, and it will be understood that the body 1 may be of any desired diameter and type and that the kerfs may be 80 of any desired depth.

Each of the container portions of the mug is preferably in the nature of a sheet 5 of suitable material, as for example, paper or parchment of rectangular or any other 85 suitable outline and these portions are preferably prepared and placed upon the market in a series comprising a continuous strip of paper perforated along transverse lines, as indicated by the numeral 6, where- 90 by the portions may be successively severed from others of their kind prior to use. In practice, the strip comprising a number of the sheets 5 is folded back and forth along the lines of perforations 6 in the manner 95 clearly shown, and between each two of the sheets there may be placed a sanitary brush comprising a tuft 7 of bristles or fibrous strands held assembled by a head 8 of any suitable construction and of any suitable 100 material. One entire side or face of the strip is provided with a coating 9 of paraf- fin or any other suitable substance capable of rendering the material of the strip im- pervious to water, and consequently each of 105 the portions or sheets 5 will have a water- proof or paraffined face or side. In order that the portions 5 may be readily placed within the upper end of the holder or body 1 of the mug, each individual sheet or por- 110 tion is scored, as at 10, along lines extend- ing inwardly at the corners thereof to points

adjacent the center of the sheet, and while these scores may extend entirely to the center, it is preferable that they terminate short of the center so that the central portion of the sheet will not be liable to crease or fold when the sheet is inserted into the holder. As before stated, the holder 1 is to be repeatedly used and in preparing the mug for use, one of the sheets 5 is separated 5 from the pack by tearing along the lines of perforations connecting it and the next adjacent sheet, and the sheet is then disposed upon the top of the holder with the score lines 10 extending above the throats of the kerfs 2 in the wall of the holder and with the central portion of the sheet located at the mouth of the said holder and pressure is then exerted in a downward direction upon the said central portion of the sheet, causing the sheet 15 to fold along the score lines 10 and its folds to engage the kerfs 2 until reaching the lower ends of the said kerfs. When this has been done, the sheet 5 will have assumed the condition shown in Figs. 3 and 4 of the 20 drawings or, in other words, will have assumed the shape of a cup of approximately rectangular form. It will be understood that the walls of the kerfs 2 serve to cause such folding of the sheet and that the marginal portions of the sheet may be pressed 25 over the lips 3 in the manner shown in Figs. 3 and 4 of the drawings, so as to protect the lips and prevent any lather or water from the container touching the holder 1. After 30 the mug has thus been formed, a suitable quantity of shaving powder or shaving cream may be placed within the mug and lather produced in the ordinary manner. While it is desirable that each of the sheets 35 40 5 be scored as indicated by the numeral 10, these score lines may be omitted if desired.

Having thus described the invention, what is claimed as new is:—

1. A shaving mug including a holder comprising a hollow body provided in its wall with spaced kerfs, and a sheet of material designed to be inserted within the end of the holder and to have portions folded by the walls of the kerfs and its folded portions received within the kerfs. 45
2. A shaving mug including a hollow holder provided in its wall at one end with a plurality of kerfs, and a sheet of material having radial scores, the said sheet of material being designed to be disposed at 50 the end of the said holder and depressed at its mid-portion, whereby the portions of the sheet adjacent and at opposite sides of the scores will be brought together within the said kerfs. 55
3. A shaving mug including a holder comprising a hollow body provided at intervals in its wall at one end with kerfs and between the kerfs being provided at its said end with lips projecting outwardly therefrom, and a sheet of material designed to be disposed upon the said end of the container and depressed within the container and to be folded by the walls of the kerfs and to have its folds received within the 60 said kerfs. 65
4. A shaving mug including a holder comprising a hollow body provided at one end with spaced portions having their upper ends outturned to form lips, and a sheet 70 of material designed to be disposed upon the said lips and to have its mid-portion depressed whereby the sheet will be folded by contact with the edges of the said 75 standing portions. 80

In testimony whereof I affix my signature.
HARRY B. RODGERS. [L.S.]
